UNITED STATES PATENT OFFICE.

WALTER V. ASH, OF PERTH AMBOY, NEW JERSEY.

RHEOSTAT.

SPECIFICATION forming part of Letters Patent No. 738,392, dated September 8, 1903.

Application filed January 2, 1903. Serial No. 137,522. (No model.)

To all whom it may concern:

Be it known that I, WALTER V. ASH, a citizen of the United States of America, and a resident of Perth Amboy, in the county of 5 Middlesex and State of New Jersey, have invented certain new and useful Improvements in Rheostats, of which the following is a specification.

My invention relates to a rheostat adapted 10 to employ the same resistances for regulating the speed of the motor that are used for including and cutting out the current of the armature of said motor, and accordingly the device considered as a whole is a compound 15 rheostat.

Generically the invention consists of a set 20 of resistances in combination with a main line for furnishing an electric current to drive an electric motor having the fields in shunt to the armature of the motor, means for including 25 said resistances in circuit with said armature and then gradually cutting out said resistances from said armature, a magnet for holding said means at its maximum limit of motion when all the resistances are cut out, 30 said magnet being so related to said means that it releases said means when either too weak or too strong by an overload on the motor, and a manual device for including and 35 regulating the number of resistances in circuit with said field-magnet after they have been cut out of the armature-circuit by said means.

My invention consists specifically of rheostat resistances adapted to be included in the 40 circuit of the armature of a shunt-motor in series with one another and to be successively and finally all cut out from said circuit by a handle turned against the action of a spring 45 which tends to return said handle to its normal phase, an iron armature carried by said arm, a magnet for said iron armature governed by the current from the armature of said motor and governing a circuit-closer for short-circuiting said magnet under too great a load 50 on the motor, said handle being adapted to return to its normal condition when said load is below a predetermined amount through the naturally-reduced power of said magnet, a pivot for said handle to turn upon, and a second handle adapted to vary the speed of said motor by including or cutting out from the field-magnet any number of the same resist-

ances that were cut out of the armature-circuit by the other handle.

Figure 1 is a plan, partly in diagram, of the 55 complete organization comprising the invention. One of the handles is in the normal phase and the other in an abnormal position. Fig. 2 is a side view of a portion of the apparatus as looked at from the left of Fig. 1. Fig. 3 is a side view of the apparatus as looked at from the right hand of Fig. 1, with the more distant parts omitted. Fig. 4 shows the pivot and spring.

The apparatus is composed particularly of the resistances 1, connecting the contact-plates 2 in the usual manner for connecting said resistances in series with one another. Some of the plates, as shown at 2', are preferably placed on an arc of smaller radius than the plates 2 for the purpose of making the device narrower. These resistances are adapted to be included in circuit with the armature 3 of the motor, whose field-magnet is indicated 70 at 4. The device for including these resistances 1 in said circuit and for cutting them out again from said circuit is the contact-piece 5, carried on the handle 6, pivoted on the pivot 7 and resisted by the action of a 75 coil-spring 8, which tends to return the handle 6 to its normal position against the stop A. After the handle 6 has been pushed to the extreme left to secure the closing of the armature and the exclusion of the resistances 1 80 said handle is to be held in that extreme position independently of the operator's hands. For this reason the iron armature 10 is provided on the handle 6 to come against the poles 11 and 12 of the magnet 13, which is in 85 the form of a solenoid having the core 14. The solenoid 13 is in the same circuit with the armature 3, as the handle 6, which is electrically connected to the contact-plate 5, so that the current can pass to said contact from 90 the binding-post 15. Therefore the magnet 13 is energized to the maximum when the armature 10 is pushed against the pole-pieces 11 and 12. However, if the load on the motor varies so as to weaken the attracting power 95 of the magnet 13 the armature 10 is released and the handle 6 is quickly returned to its normal position by the action of the spring 8. Means are provided also for returning this 100 handle to its normal position if the load is so heavy that the core 14 is abnormally attracted,

for then the circuit-closer 16, carried by the core 14, comes in contact with the terminals 18 of the magnet 13 and short-circuits the latter, thereby similarly releasing the handle 6, and 5 the spring 19, being provided for the circuit-closer 16, returns it to its normal position, away from the terminals 18.

The handle 20 is for varying the speed of the motor by including the same resistances 1 10 or excluding some of them from the circuit of the field-magnet, and said handle 20 is carried by the same pivot 7, thereby securing means for using the same resistances 1 both for starting and stopping the motor and for 15 varying the speed of the motor. The contact-plate on the handle 20 is number 21. The current is from the positive pole of the dynamo 22 through the hand-switch 23, to the binding-post 15, through the handle 20, through 20 one or more resistances 1, according to the position of the handle 20, then to the contact-plate 2' at the extreme right, then through the field-magnet coil 4, and back to the negative pole of the dynamo. Thereby the movement 25 of the handle 20 will vary the number of resistances of the resistance-coil 1, in circuit with the field-magnet coils of the motor, for varying the speed of the motor.

The complete operation is as follows: The 30 handle 6 is turned by hand until the armature 10 is held by the pole-pieces 11 and 12, the switch 23 having been closed by hand to begin with. The motor then runs, with the full current possible, through the field-magnet. 35 The speed may be varied by turning the handle 20 back and forth over the contacts 2 and 2'. If the load becomes too great, the magnet 13 is short-circuited and the handle 6 is released from the solenoid, or if the load is too 40 little the handle is automatically released. The spring 8 has nothing to do with the action of the handle 20, which is merely pivoted and adapted to remain on any contact 2 or 2' when the operator's hand is removed, but is 45 returned by the recoil of the handle 6.

I claim as my invention—

1. The combination of resistances in series circuit with each other, main-line conductors, armature of a motor, field-magnet of the motor, means for including said resistances in circuit with the armature, and then gradually cutting out said resistances from the armature, a magnet included in the armature-circuit for holding said means, at the position 55 where the resistances are cut out, for substantially only a normal load upon said motor, and a manual device for independently including and regulating the number of said resistances in circuit with said field, after 60 they have been cut out of the armature-circuit by said means.

2. The combination of resistances in series circuit with each other, main-line conductors, armature of a motor, field-magnet of the motor, means for including said resistances in circuit with the armature, and then gradually cutting out said resistances from the arm- 65

ture, a magnet included in the armature-circuit for holding said means, at the position where the resistances are cut out, for substantially only a normal load upon said motor, and a manual device for independently including and regulating the number of said resistances in circuit with said field, after 70 they have been cut out of the armature-circuit by said means, said means carrying an iron armature to be attracted and held by said magnet at a predetermined load on the motor and to be released when the load decreases. 75

3. The combination of resistances in series circuit with each other, main-line conductors, armature of a motor, field-magnet of the motor, means for including said resistances in circuit with the armature, and then gradually 85 cutting out said resistances from the armature, a magnet included in the armature-circuit for holding said means, at the position where the resistances are cut out, for substantially only a normal load upon said motor, a manual device for independently including and regulating the number of said resistances in circuit with said field, after 90 they have been cut out of the armature-circuit by said means, said means carrying an iron armature to be attracted and held by said magnet at a predetermined load on the motor and to be released when the load decreases. 95

4. The combination of resistances in series circuit with each other, main-line conductors, armature of a motor, field-magnet of the motor, means for including said resistances in circuit with the armature, and then gradually 105 cutting out said resistances from the armature, a magnet included in the armature-circuit for holding said means, at the position where the resistances are cut out, for substantially only a normal load upon said motor, a manual device for independently including and regulating the number of said resistances in circuit with said field, after 110 they have been cut out of the armature-circuit by said means, said means carrying an iron armature to be attracted and held by said magnet at a predetermined load on the motor and to be released when the load decreases, a spring for returning said means when released by said magnet, and a handle on said means. 115

5. The combination of resistances in series circuit with each other, main-line conductors, armature of a motor, field-magnet of the motor, means for including said resistances in circuit with the armature, and then gradually 125 cutting out said resistances from the armature, a magnet included in the armature-circuit for holding said means, at the position where the resistances are cut out, for substantially only a normal load upon said motor, a manual device for independently including and regulating the number of said resistances in circuit with said field, after 130 they have been cut out of the armature-circuit by said means,

5 said means carrying an iron armature to be attracted and held by said magnet at a predetermined load on the motor and to be released when the load decreases, a spring for returning said means when released by said magnet, a handle on said means, and a circuit-closer governed by the current of said magnet for short-circuiting said magnet when the load on the motor is greater than a predetermined 10 amount.

6. The combination of resistances in series circuit with each other, main-line conductors, armature of a motor, field-magnet of the motor, means for including said resistances in 15 circuit with the armature, and then gradually cutting out said resistances from the armature, a magnet included in the armature-circuit for holding said means, at the position where the resistances are cut out, for substantially only a normal load upon said motor, a manual device for independently including 20 and regulating the number of said resistances in circuit with said field, after they have been cut out of the armature-circuit by said means, 25 and a circuit-closer governed by the current of said magnet for short-circuiting said magnet when the load on the motor is greater than a predetermined amount.

7. The combination of resistances in series 30 circuit with each other, main-line conductors, armature of a motor, field-magnet of the motor, means for including said resistances in circuit with the armature, and then gradually cutting out said resistances from the armature, a magnet included in the armature-circuit for holding said means, at the position where the resistances are cut out, for substantially only a normal load upon said motor, a manual device for independently including 35 and regulating the number of said resistances in circuit with said field, after they have been cut out of the armature-circuit by said means, said means carrying an iron armature to be attracted and held by said magnet at a predetermined load on the motor and to be released when the load decreases, and a circuit-closer governed by the current of said magnet for short-circuiting said magnet when the load on the motor is greater than a predetermined 45 amount.

8. The combination of resistances in series 50 circuit with each other, main-line conductors, armature of a motor, field-magnet of the motor, means for including said resistances in circuit with the armature, and then gradually cutting out said resistances from the armature, a magnet included in the armature-circuit for holding said means, at the position where the resistances are cut out, for substantially only a normal load upon said motor, a manual device for independently including 55 and regulating the number of said resistances in circuit with said field, after they have been cut out of the armature-circuit by said means, said means carrying an iron armature to be attracted and held by said magnet at a predetermined load on the motor

and to be released when the load decreases, a spring for returning said means when released by said magnet, and a circuit-closer 70 governed by the current of said magnet for short-circuiting said magnet when the load on the motor is greater than a predetermined amount.

9. The combination of resistances in series 75 circuit with each other, main-line conductors, armature of a motor, field-magnet of the motor, means for including said resistances in circuit with the armature, and then gradually cutting out said resistances from the 80 armature, a magnet included in the armature-circuit for holding said means, at the position where the resistances are cut out, for substantially only a normal load upon said motor, a manual device for independently including 85 and regulating the number of said resistances in circuit with said field, after they have been cut out of the armature-circuit by said means, said means carrying an iron armature to be attracted and held by said magnet at a predetermined load on the motor and to be released when the load decreases, a spring for returning said means when released by said magnet, a handle on said means, and a circuit-closer governed by the current 90 of said magnet for short-circuiting said magnet when the load on the motor is greater than a predetermined amount.

10. The combination of resistances in series 95 circuit with each other, main-line conductors, 100 armature of a motor, field-magnet of the motor, means for including said resistances in circuit with the armature, and then gradually cutting out said resistances from the armature, a magnet included in the armature-circuit for holding said means at the position 105 where the resistances are cut out, for substantially only a normal load upon said motor, a manual device for independently including 110 and regulating the number of said resistances in circuit with said field, after they have been cut out of the armature-circuit by said means, said means carrying an iron armature to be attracted and held by said magnet at a predetermined load on the motor and to be released when the load decreases, a spring 115 for returning said means when released by said magnet, and a circuit-closer governed by the current of said magnet for short-circuiting said magnet when the load on the motor is greater than a predetermined amount, and a spring normally holding said circuit-closer open.

11. The combination of resistances in series 120 circuit with each other, main-line conductors, 125 armature of a motor, field-magnet of the motor, means for including said resistances in circuit with the armature, and then gradually cutting out said resistances from the armature, a magnet included in the armature-circuit for holding said means, at the position 130 where the resistances are cut out, for substantially only a normal load upon said motor, a manual device for independently including

and regulating the number of said resistances in circuit with said field, after they have been cut out of the armature-circuit by said means, said means carrying an iron armature to be attracted and held by said magnet at a pre-determined load on the motor and to be released when the load decreases, and a spring for returning said means when released by said magnet, a handle on said means, a circuit-closer governed by the current of said magnet for short-circuiting said magnet when the load on the motor is greater than a pre-determined amount, and a spring normally holding said circuit-closer open.

12. The combination of resistances in series circuit with each other, main-line conductors, armature of a motor, field - magnet of the motor, means for including said resistances in circuit with the armature, and then gradually cutting out said resistances from the armature, a magnet included in the armature-circuit for holding said means, at the position where the resistances are cut out, for substantially only a normal load upon said motor,

25 a manual device for independently including and regulating the number of said resistances in circuit with said field, after they have been cut out of the armature-circuit by said means, and a single pivot for said means and for said 30 device to turn upon.

13. The combination of resistances in series circuit with each other, main-line conductors, armature of a motor, field - magnet of the motor, means for including said resistances in circuit with the armature, and then gradually cutting out said resistances from the armature, a magnet included in the armature-circuit for holding said means, at the position where the resistances are cut out, for substantially only a normal load upon said motor, a manual device for independently including and regulating the number of said resistances in circuit with said field, after they have been cut out of the armature-circuit by said means, 45 said means carrying an iron armature to be attracted and held by said magnet at a pre-determined load on the motor and to be released when the load decreases, a spring for returning said means when released by said 50 magnet, and a single pivot for said means and for said device to turn upon, said magnet being in the form of a solenoid with pole-pieces, an armature for said pole-pieces carried by said means, a core for said solenoid, 55 a circuit-closer carried by said core, terminals for the solenoid adapted to be closed by said circuit-closer for short-circuiting said magnet, and a spring for holding said circuit-closer open.

60 14. The combination of resistances in series circuit with each other, main-line conductors, armature of a motor, field-magnet of the motor, means for including said resistances in circuit with the armature, and then gradually cutting out said resistances from the armature, a magnet included in the armature-circuit for holding said means, at the position

where the resistances are cut out, for substantially only a normal load upon said motor, a manual device for independently including and regulating the number of said resistances in circuit with said field, after they have been cut out of the armature-circuit by said means, said means carrying an iron armature to be attracted and held by said magnet at a predetermined load on the motor and to be released when the load decreases, a spring for returning said means when released by said magnet, a handle on said means, and a single pivot for said means and for said device to turn upon. 70 75 80

15. The combination of resistances in series circuit with each other, main-line conductors, armature of a motor, field-magnet of the motor, means for including said resistances in circuit with the armature, and then gradually cutting out said resistances from the armature, a magnet included in the armature-circuit for holding said means, at the position where the resistances are cut out, for substantially only a normal load upon said motor, a manual device for independently including and regulating the number of said resistances in circuit with said field, after they have been cut out of the armature-circuit by said means, said magnet being in the form of a solenoid with pole-pieces, an armature for said pole-pieces carried by said means, a core for said solenoid, a circuit-closer carried by said core, terminals for the solenoid adapted to be closed by said circuit-closer for short-circuiting said magnet, and a spring for holding said circuit-closer open. 85 90 95 100

16. The combination of resistances in series circuit with each other, main-line conductors, armature of a motor, field-magnet of the motor, means for including said resistances in circuit with the armature, and then gradually cutting out said resistances from the armature, a magnet included in the armature-circuit for holding said means, at the position where the resistances are cut out, for substantially only a normal load upon said motor, a manual device for independently including and regulating the number of said resistances in circuit with said field, after they have been cut out of the armature-circuit by said means, a single pivot for said means and for said device to turn upon, said magnet being in the form of a solenoid with pole-pieces, an armature for said pole-pieces carried by said means, a core for said solenoid, a circuit-closer carried by said solenoid, terminals for the solenoid adapted to be closed by said circuit-closer for short-circuiting said magnet, and a spring for holding said circuit-closer open. 105 110 115 120 125

In testimony whereof I have hereunto subscribed my name and affixed my seal this 19th day of December, 1902.
